UNITED STATES PATENT OFFICE.

JAMES T. RYAN, OF FRANKFORT, KENTUCKY.

ROTARY PUMP OR THE LIKE.

Application filed October 25, 1924. Serial No. 745,843.

To all whom it may concern:

Be it known that I, JAMES T. RYAN, a citizen of the United States, residing at Frankfort, in the county of Franklin and State of Kentucky, have invented certain new and useful Improvements in Rotary Pumps or the like, of which the following is a specification.

The invention relates to pumps, and has as an object the provision of a rotary pump which may be operated in a well in the space usually devoted to the well casing. If desired, the apparatus may be placed inside an ordinary well casing.

15 An object of the invention is the provision of a rotary pump having a novel form of centrifugal piston, which piston may be utilized in fluid pressure operated motors as well as pumps.

20 A further object of the invention is the provision of a rotary pump which may be operated in stages, and wherein one pump feeds the next higher stage, so as to reduce the hydraulic head upon each individual 25 pump.

Further objects of the invention will appear from the following description when read in connection with the accompanying drawings showing illustrative embodiments 30 of the invention, and wherein

Fig. 1 is a central section, partly in elevation, showing the invention applied to two stages.

Fig. 2 is a like section of the lower stage.

35 Figs. 3 and 4 are horizontal sections on the lines 3, 3 and 4, 4 respectively of Figure 2.

Fig. 5 is a detail, horizontal section showing a modified form of rotor utilizing a plurality of valves.

40 Fig. 6 is a side elevation of the rotor of Figs. 1 to 4 inclusive.

Fig. 7 is a vertical section of the rotor on the line 7, 7 of Fig. 6.

Fig. 8 is a central vertical section of a 45 horizontal form of the invention.

Fig. 9 is a detail sectional view on the line 9, 9 of Fig. 8.

Fig. 10 is a section corresponding to Fig. 8 of a still further modification and

50 Fig. 11 is a perspective view of the piston.

As shown in Fig. 1 the device comprises an outer casing 10, and an inner rotating member 11, the latter member projecting to the top of the well and adapted to be rotated by power applied to the vertical shaft

12. The rotating member 11 is desirably

formed of lengths of pipe 13 having screw threaded connection with rotors 14. Each rotor 14 is shown as formed of a cylindrical body having a concave recess 15 shown most clearly on Fig. 4, and a rod 16 extending longitudinally of the recess. The rod 16 may be desirably secured to the body 14 by seating in the recess 17 at each end of the depression 15 and by being secured therein by means of bolts 18, 19.

A piston 20 is shown as formed with an arcuate outline, one surface fitting the rod 16 and the opposite surface fitting the bottom of the recess 15. The ends of the pistons 20 are formed as illustrated so that when the rotor is in a position wherein the valve is entirely housed in the recess 15 the ends thereof may be substantially flush with the surface of the rotor 14. The arcuate 75 extensions 90 of the piston 20, shown most clearly in Fig. 11, act to guide the piston in its sliding motion.

The rotor 14 is shown as mounted for revolution in a cylinder 21 or 22, the former being the form of cylinder where but one stage of the pump is used, or the lowest stage of a multi-stage pump. In each case the rotor 14 is concentric with the exterior of the cylinder 21, and rotates in a cylindrical cavity 23 formed eccentric with the body of the cylinder so as to form a crescent shaped cavity between the rotor and the cylinder.

Inlet ports 24 are shown in the outer wall 90 of the cylinder 21 and in the partition 25 of the cylinder 22. Outlet ports 26 are shown in the partition 27 of both cylinders 21 and 22.

To connect the cylinders 21, 22 with the casing 10 the ends of the cylinders are shown as formed with an interior screw thread 28 engaging exterior screw threads on a coupling member 29, which latter has screw threaded engagement with the casing 10. A passage 30 is shown in each of the couplings 29 to permit the upward flow of water passing ports 26, the passages having communication with the cavities 31 between the outer wall of the cylinder 21, 22 and the partition 27. The coupling member 29 above the lowest stage is also shown provided with a passage at 32 to permit fluid to flow upwardly within the casing 10 and about the rotating member 11 to reach the fluid ports 24 110 of the second stage.

If desired, a bushing 33 may be placed

adjacent the top of the well or at other points between the individual pumps to steady the motion of the rotating member 11, and if such bushings are provided each is 5 formed with a channel 34 to permit the flow of fluid upwardly within the casing 10. An outlet 35 is shown for the fluid at the top of the casing.

To prevent the back flow of fluid into the 10 cavity 23 and out of the intake ports 24, after the piston 20 has swept past the fluid ports 26, a check valve in the form of a flat valve 36 is shown, being most clearly disclosed in Fig. 4. In the embodiment of the 15 invention employing a plurality of pistons a check valve will be of less importance, if needed.

If desired, a cavity 45, shown as cylindrical in form, may be provided in the body of the 20 rotor 14, to preserve the dynamic balance by compensating for the material left out of the cavity 15 and because of the space 46 in the piston 20. The latter space is provided in the piston 20 to unbalance the 25 valve, whereby the centrifugal force will throw the working end of the same outwardly instead of the non-working end thereof.

The amount of pressure of the piston 20 produced by centrifugal force upon the 30 rotation of the rotor 14 may be controlled by the choice of radius of the surface of the piston recess 15. The friction of the piston 20 on the cylinder wall 23 may likewise be controlled by the location of the center of 35 the surface 47 of the piston thrust rod 16, it being possible to place the center of rotation of the piston 20 about the rod 16 outside of the body of the rotor. The pressure of the piston 20 against the liquid in the cavity 40 23 by virtue of which the water is caused to pass through the pump, is borne by the surface of the recess 15, and does not tend to retract the valve into the recess, because of the fluid pressure on the surface 92.

45 In the form of the invention shown in Fig. 5 a plurality of pistons 20' are illustrated, and oil conduits 38' are shown to lubricate the piston retaining rods. The oiling device consists of a central oil conduit 50 in the rotor 14' with smaller radial oil conduits extending near the ends of the rotor to suitable oil holes in the piston retaining rods. Communicating with the above radial conduits are oil holes extending lengthwise of 55 the rods and feeding to the desired points on the surface between the pistons 20' and the rod. It is understood that means of lubricating the rod frictional surfaces will not be necessary except where the invention is 60 used as a blower or motor.

In the form of the horizontal device shown 65 at 74, for use with larger pumps or motors, and is indicated as in the form of a hollow casing having arcuate walls 75 for delimit-

ing the piston recesses, and end walls 76 having central openings therein to receive the shaft 77 which is keyed thereto. The piston rods 78 are shown as secured to the ends 76 by means of screws 79. It will be noted that 70 the piston rod is cut away as illustrated at 51 in Figs. 4, 5, 8 and 10, to permit the pumping action of the piston to be effective when the piston recedes into the cavity 15 at the end of its stroke. A pulley 80 is shown mounted 75 upon the shaft 77, the end of which shaft is carried in a journal 81 upon a standard 82, carried by the base 83. In this form of the invention the inlet pipe when used as a pump is shown at 84 and the outlet pipe at 85. 80

The form of the device shown in Fig. 10 differs from that in Figs. 8 and 9 by the fact that the interior of the cylinder is formed on the arcs of different circles, the 85 circles intersecting but not being tangent at any point. With this form of device, the arc 86 may be caused to fit the rotor throughout a substantial portion of its periphery.

In the operation of the device as a pump, the rotor is revolved in the direction of the 90 arrows Figs. 4, 5, 8 and 10, and the piston caused to press against the interior of the cylinder by centrifugal force, the fluid pressure on the surface 91 holding it firmly seated 95 against the cylinder wall.

As the piston is thrown out of the body of the rotor at a point adjacent the fluid intake port, the cavity ahead of the piston is at its greatest volume, and the volume thereof in front of the piston is reduced until the outlet port is passed, whereby the piston sweeps fluid to and through the outlet ports. 100

Minor changes may be made in the physical embodiment of the invention, and the particular form of rotor and piston may be 105 utilized in either a pump or motor without departing from the spirit of the invention.

I claim:

1. In a device of the class described a cylinder, a rotor eccentrically mounted therein and having a piston-receiving recess, an arcuate piston seating in said recess and adapted to be projected therefrom by centrifugal force, and a piston rod extending transversely of said recess acting to retain 115 said piston therein.

2. In a device of the class described, in combination, a cylinder, a rotor mounted eccentrically to revolve therein, an arcuate piston slidably carried by said rotor to be pressed against the wall of the cylinder by centrifugal force, said piston subtending an arc of said rotor when fully housed therein and inlet and outlet ports for said cylinder. 120

3. In a device of the class described, in combination, a cylinder, a rotor mounted eccentrically in relation to said cylinder to revolve therein, arcuate pistons slidably mounted in said rotor and when fully housed therein each subtending an arc of the rotor, 125 130

said pistons adapted to be pressed against the wall of the cylinder by centrifugal force and the fluid pressure, and inlet and outlet ports for said cylinder.

5 4. A rotary pump comprising, in combination, a cylinder, a rotor eccentrically mounted therein, a centrifugally actuated piston slidably carried by said rotor, an inlet port and an outlet port communicating with 10 said cylinder, the latter opening into an outlet chamber, a cylinder head having a passage communicating with said chamber.

5 5. In a device of the class described, in combination, a cylinder, a rotor eccentrically mounted therein, an arcuate piston slidably carried by said rotor and when completely housed therein occupying a position substantially symmetrical therewith, and means to unbalance the centrifugal force 20 upon said piston.

6 6. In a device of the class described, in combination, a cylinder, a rotor eccentrically mounted therein, arcuate pistons slidably carried by said rotor and when completely housed therein subtending arcs of 25 said rotor, each of said pistons having a cavity in one edge to unbalance the centrifugal force thereon, and inlet and outlet ports for said cylinder.

30 7. In a device of the class described, in combination, a cylinder, a rotor eccentrically mounted therein, an arcuate piston slidably carried by said rotor and when completely housed therein occupying a position substantially symmetrical therewith, a piston retaining rod carried by the rotor within 35 the arc of the piston, and inlet and outlet ports for said cylinder.

8. In a device of the class described, a 40 piston comprising an elongated body arcuate transversely of its length and having arcuate extensions at its ends.

9. In a device of the class described, in combination, a cylinder, a cylindrical rotor 45 mounted to revolve therein eccentric thereto and having a recess in its surface, a rod spanning said recess, the outer surface of said rod lying within the circumference of the rotor, the inner surface of the rod concentric with the wall of the recess, an arcuate piston slidably within said recess and 50 behind said rod adapted to be pressed against the wall of said cylinder by centrif-

ugal force, and inlet and outlet ports for 55 said cylinder.

10. A rotary pump comprising, in combination, a cylinder, a head for said cylinder having external pipe receiving threads and a pump rod journal, the cylinder chamber being eccentric to said journal, a rotor 60 mounted in said cylinder upon a rod revolving in said journal, a piston slidably mounted in said rotor adapted to be pressed against the cylinder wall by centrifugal force and fluid pressure, inlet and outlet 65 ports for said cylinder, the latter communicating with a chamber in a wall of said cylinder, and said head having a port for passage of fluid from said chamber to the interior of a pipe connected to the head. 70

11. A rotary pump comprising, in combination, a cylinder having an eccentric chamber therein and an outlet chamber in a wall thereof, cylinder heads for said cylinder, one of said heads having external 75 threads to connect with a pipe and an outlet passage to place said outlet chamber in communication with said pipe, a pump rod journaled in said threaded head, a rotor connected to said rod and a centrifugally operated piston carried by said rotor. 80

12. A two stage rotary pump comprising, in combination, a first stage pump connected to the end of a pipe comprising a head for said pump, a pump rod journaled 85 in said head, a rotor operated by said rod, said head having an outlet port communicating with the interior of said pipe, a second stage pump comprising a lower head connected to said pipe and having a port there-through feeding the second stage pump, said pump rod journaled in said lower head, 90 a cylinder connected to said lower head having inlet and outlet chambers formed in its walls, the former communicating with said last named port, a rotor revolving in said second stage cylinder connected at its lower end to said pump rod and at its upper end to a continuation thereof, an upper head for 95 said second stage cylinder having an outlet port placing the outlet chamber in communication with the pipe connected thereto, the pump rod journaled in said last-named head. 100

JAMES T. RYAN.
